UNITED STATES PATENT OFFICE

2,217,799

HYDRAULIC PRESS

Jean V. Glesler, Knoxville, Tenn., assignor to The
Fulton Sylphon Company, Knoxville, Tenn., a
corporation of Delaware

Application March 30, 1938, Serial No. 199,056

29 Claims. (Cl. 153—73)

This invention relates to hydraulic presses and more particularly to hydraulic presses for forming expandible and contractible corrugated metallic vessels.

5 Heretofore various devices have been proposed for forming expandible and contractible corrugated metallic vessels by spacing forming plates along a metallic tube at regular intervals, thereafter expanding the tube by internal hydraulic pressure until bulges form in the tube between plates and thereafter forcing the forming plates toward each other to form corrugations in the tube between plates. In these devices many of the steps in the process of forming the expandible and contractible vessels have been performed manually resulting in low production rates and have introduced difficulties arising from the human factor of the operators.

The present invention obviates these prior difficulties though using the broad idea of forming expandible and contractible metallic vessels by spacing equidistantly a plurality of forming plates along a metallic tube, expanding the tube by hydraulic pressure forming bulges in the tube between the forming plates, and thereafter forcing the forming plates together to form the desired corrugations in the tube by providing automatic operation in the sequence of its functions thus producing a uniform product at greatly increased rates.

In the present invention the operator places the metallic tube to be formed into the expandible and contractible vessel within the forming plates. In locking the forming plates about the tube the operator automatically actuates suitable means for advancing other suitable means for closing the open end or ends of the tube. Thereafter hydraulic pressure is automatically exerted within the tube to form bulges in the tube between the forming plates.

40 When the hydraulic pressure reaches a predetermined value it is thereafter automatically maintained at this pressure and at the same time suitable means are automatically energized to remove spacers from between the forming plates. Upon removal of these spacers means are actuated automatically to force the plates toward each other to form the desired corrugations in the tube between the plates. When the plates reach a predetermined relationship

sel from the forming plates, manually returns the spacers between the several forming plates and places another tube within the forming plates to start another forming cycle.

It is accordingly an object of the present invention to provide a novel hydraulic press for forming expandible and contractible corrugated metallic vessels in which a metallic tube is subjected to internal pressure to expand it between forming plates which are thereafter forced together to form the corrugated vessel. 5

It is another object of this invention to provide a novel hydraulic press in which the several steps of forming the expandible and contractible vessel are automatically performed at 15 the proper time.

Another object of this invention is to provide a novel hydraulic press in which novel means are automatically actuated when the forming plates are locked together to automatically seal 20 the open end or ends of the tube.

Another object of this invention is to provide a novel hydraulic press in which novel means are used to seal the end or ends of the tube.

Another object of this invention is to provide 25 a novel hydraulic press in which novel means are automatically actuated to introduce hydraulic pressure within the tube when the end or ends of the tube are sealed.

Another object of this invention is to provide 30 a novel hydraulic press in which novel means are provided for maintaining the hydraulic pressure within the tube at a predetermined value.

Another object of this invention is to provide a novel hydraulic press in which novel means 35 are provided for generating the hydraulic pressure for use within the tube.

Another object of this invention is to provide a novel hydraulic press in which novel means are automatically actuated when the hydraulic 40 pressure within the tube has reached a predetermined value to remove the spacers from between the forming plates.

Another object of this invention is to provide 45 a novel hydraulic press in which novel means are provided to force the forming plates together which means are automatically actuated as soon as the spacers have been removed from between the forming plates.

Another object of this invention is to provide 50 a novel hydraulic press in which novel means are automatically actuated when the forming plates have been forced together a predetermined amount to release the pressure forcing the forming plates together.

Another object of this invention is to provide a novel hydraulic press in which novel means are provided for automatically reducing the hydraulic pressure within the formed vessel as soon as the forming plates have been forced together a predetermined amount.

Another object of this invention is to provide a novel hydraulic press in which novel means are provided for automatically removing the end sealing means as soon as the forming plates have been forced together a predetermined amount.

Another object of this invention is to provide a novel hydraulic press in which the steps of forming the expandable and contractible corrugated metallic vessel are automatically carried out in proper sequence by hydraulic pressure.

Another object of this invention is to provide a novel hydraulic press in which novel means are provided for locking the forming plates together.

Another object of this invention is to provide a novel hydraulic press in which novel means are provided for manually interposing the spacers between the forming plates.

Another object of this invention is to provide a novel hydraulic press in which novel means are provided for mounting the forming plates.

Another object of this invention is to provide a novel hydraulic press in which novel means are provided for mounting the forming plates to allow their ready removal for repair or replacement.

Another object of this invention is to provide a novel hydraulic press in which novel means are provided for adjusting the relative position of the spacers.

Another object of this invention is to provide a novel hydraulic press in which novel means are provided for mounting the spacers to allow their ready removal for repair or replacement.

Other and further objects of this invention will appear as the description thereof proceeds.

With these objects in view an illustrative embodiment of the novel hydraulic press of the present invention is shown in the accompanying drawings but it is to be expressly understood that this embodiment is shown and will hereafter be described for the purpose of illustration only and should not be construed as a limitation of the present invention. Reference should be had to the appended claims to determine the scope of the present invention.

In the accompanying figures Fig. 1 is a front view of one embodiment of my novel hydraulic press;

Figs. 2 and 3 are together a rear view of the embodiment of my novel hydraulic press shown in Fig. 1 but including the hydraulic reservoir not shown in Fig. 1;

Fig. 4 is an enlarged view of a portion of Fig. 1 showing in more detail the forming plates, their novel locking means, the novel end sealing means, and the ram for forcing the forming plates together;

Fig. 5 is an enlarged view of a portion of Fig. 1 as seen from the top showing in more detail the novel cradle carrying the forming plates, the novel cradle lock, and the novel spacer support;

Fig. 6 is a more detailed showing of the novel spacer actuating means shown in Fig. 1 as seen from the left in Fig. 1;

Fig. 7 is an exploded and enlarged view of the pilot valve shown in Fig. 5;

Fig. 8 is an enlarged view of a pair of cooperating forming plates as shown in Fig. 1 showing

in more detail the novel locking means and the positioning of the springs between the forming plates;

Fig. 9 is a cross section of a portion of Fig. 1 as seen from the right in Fig. 1 showing in more detail the novel end plate, novel plate locking means and novel cradle locking means;

Fig. 10 is a cross section on the line 10-10 in Fig. 8 showing the interlocking construction of each pair of forming plates at their pivot;

Fig. 11 is a partial cross section as viewed from the top in Fig. 1 of any two adjacent forming plates showing in full lines the position of one of the springs between adjacent forming plates in expanded position and showing in dotted lines the position of the spring in contracted position;

Fig. 12 is a side view in more detail of the novel cradle locking means shown in Fig. 1 here shown in locked position;

Fig. 13 is a vertical sectional view along the axis of the embodiment of the present invention shown in Fig. 1 showing the tube end sealing means, the tube in position in the forming plates and the relative position of the end plate and ram at the beginning of the cycle but before interposing the spacers;

Fig. 14 is an enlarged and more detailed view of a portion of Fig. 13 showing the spacers in position between the forming plates;

Fig. 15 is a sectional view of the tube in the forming plates after hydraulic pressure has formed bulges in the tube between the forming plates;

Fig. 16 is a sectional view of the tube in the forming plates after the forming plates have been forced together;

Fig. 17 and Fig. 17a are fragmentary side views of the tube clamping members used with one embodiment of the novel tube end sealing means of the present invention;

Fig. 18 is an end view of the embodiment of the novel tube end sealing means as seen from the right in Fig. 17;

Fig. 19 is a vertical section of the pressure booster used with the embodiment of the present invention shown in Fig. 1;

Fig. 20 is a sectional view in more detail of the embodiment of the tube end sealing means shown in Fig. 1;

Fig. 21 is an enlarged view of a portion of Fig. 20;

Fig. 22 is a sectional view of another embodiment of my novel tube end sealing means; and

Fig. 23 is a view of the embodiment of the tube end sealing means of Fig. 22 showing the tube sealed therein.

In the several figures, in which like reference characters indicate similar parts, and more particularly with reference to Figs. 1, 2, 3, 4 and 5, 11 is any suitable machine bed longitudinally slotted at 12 for mounting the several parts of the device and supported by suitable legs 13. Mounted at one end of bed 11 are brackets 14 and 15 between which is carried a ram piston and cylinder 16, bolts 17 acting to hold the assembly together. Fluid under pressure is admitted to one side of the piston in cylinder 16 through hand-adjusted valve 18 and to the other side of the piston through hand-adjusted valve 19. Carried by the piston in cylinder 16 and projecting through a suitable stuffing box 20 is the ram shaft 21 terminating in a ram head 22 which is threaded on shaft 21 to allow longitudinal adjustment along the length of shaft 21.

Carried by bed 11 adjacent ram head 22 is

cradle base 23 having uprights 24 and 25 secured thereto and carrying a top member 26 (see Fig. 4). Upright 24 is cut away at 27 to allow the end sealing assembly to partially pass therethrough and upright 25 is suitably cut away to allow ram shaft 21 to pass therethrough. Carried between uprights 24 and 25 is guide rod 28 upon which is slidably mounted any suitable number of non-pivoted forming plates 29 and pivoted forming plates 36, rod 28 also carrying a stop sleeve 30 to limit the expansive movement of plates 29 and 36. Also carried between uprights 24 and 25 is a guide rod 31 upon which said plates 29 are also designed to slide and upon which is mounted a stop sleeve 32 to limit the expansive movement of plates 29. Pivotedly mounted on rod 28 are cradle end members 33 and 34 carrying a top member 35 (Fig. 9) and supporting between them on guide rod 37 the forming plates 36, guide rod 37 being carried by said cradle members 33 and 34 and having mounted thereon a stop sleeve 38 to limit the expansive movement of plates 36. Plates 29 and 36 are arranged in cooperating pairs each pair of plates being interlocked at their pivot point about rod 28 as shown in Fig. 10 and being provided with a bearing bushing 39 as shown in Fig. 8 in sliding engagement with rod 28. Each of plates 29 and 36 are semicircularly recessed at 40 and 41 respectively (Fig. 8) to form a circular die when each pair of plates is locked together, plates 29 and 36 being cut away at 41' and 42 respectively to receive the bends of metal of the finished product as will be more fully described hereafter. Plates 29 and 36 are also recessed on both sides at 43 and 44 respectively to receive springs 45, springs 45 having outturned ends 46 (Fig. 11) to engage slots 47 and operating to force the several pairs of plates apart. Each of plates 29 has formed thereon an upwardly extending tongue 48 on which is pivotally mounted at 49 a latch 50 designed to engage over an upwardly extending tongue 51 on each of plates 36 to lock each pair of plates together. Each latch 50 carries a tongue 52 which is bored at 53 to slidably receive a release rod 54. Release rod 54 is carried at each end by links 55 secured to a rocking shaft 56 which extends through the cradle latch member 57 (Fig. 4). Cradle latch member 57 is pivotally mounted at 58 (Fig. 9) on brackets 59 carried by top member 26.

Cradle latch member 57 terminates at one extremity in downwardly turned latch fingers 60 carrying between them a lock bar 61 and is recessed at 62 at its opposite extremity to receive a gear 63 rotatable about pivot 58 with cradle latch member 57. Cradle latch member 57 is provided with a stop 64 to limit its upward motion about pivot 58. Suitably secured to top member 26 are rearwardly extending arms 64 between which is rotatably mounted a shaft 65 carrying thereon a gear 66 in engagement with gear 63 and having mounted thereon at opposite extremities cranks 67 carrying pins 68. Attached to rocking bar 56 and engaging pins 68 are springs 69.

Pivotedly mounted on an extension 10 of cradle base 23, at 71, is cradle latch lever 72 which passes through a slot in an extension 13 of top member 35 and terminates in a hand grip 74. Lever 72 is slotted at 75 to slidably receive the pin 76 of the latch bar 77 terminating in fingers 78 and 79. Latch bar 77 is pivotally mounted, as at 80, on upturned flanges 81 of extension 13. Lever 72 is provided with a shoulder 82 to engage

under extension 13 when the cradle is locked together. Top member 35 is recessed at 83 (Fig. 12) to receive fingers 60 of latch member 57 (Fig. 12).

With particular reference now to Figs. 5 and 6, secured to bed 11 and extending rearwardly therefrom is track 84 upon which is mounted a slide 85. Slide 85 has formed therewith arms 86 extending parallel to bed 11 and terminating in upturned members 87 having bearing screws 88 mounted therein. Arms 86 also carry bearing blocks 89 having bearing caps 90, a spacer support rod 91 being carried by bearing blocks 89 beneath caps 90 and being centered by screws 88. Suitably mounted on spacer support rod 91 are a plurality of spacers 92 designed to slide between the pairs of forming plates 29 and 36 to suitably space them. Slide 85 is moved on track 84 to move spacers 92 into or out of position between the pairs of forming plates 29 and 36 by a link 93 pivoted to slide 85 at 94 and pivotally engaging a second link 95 at 96, link 95 being carried by a shaft 96 rotatably mounted in brackets 97 secured to bed 11, shaft 96 being rotated by a manually operable lever 98 or by suitable hydraulic means to be hereafter described engaging an arm 99 likewise secured to shaft 96.

Mounted at the other end of bed 11 opposite cylinder 16 is a cylinder 100 suitably supported by brackets 101 secured to bed 11, the cylinder assembly being held together by bolts 102. The position of the cylinder assembly may be varied by adjusting screw 103 secured to bed 11. Fluid under pressure is admitted to one side of piston 104 in cylinder 100 through a flexible conduit 105 and to the other side through a flexible conduit 106. Secured to piston 104 is piston rod 107 (Figs. 13, 20 and 21) which passes outward through extension 108 of bracket 101, suitable packing being provided at 109 to prevent the escape of liquid from cylinder 100. Piston rod 107 is internally bored and threaded at its outer end as at 110. Suitably mounted on extension 108 of bracket 101 as by threads 111 is hollow end seal assembly housing 112 longitudinally slotted at 113 and 114 and closed by the end cap 115 which is internally threaded at 116 (Fig. 20). Threaded into boring 110 of piston rod 107 and locked in place by lock nut 117 is extension 118 upon which is mounted collet clamping member 119 secured thereto by through pin 120. Collet clamping member 119 is centrally bored at 121 and longitudinally slotted at 122. Central boring 121 is enlarged at 123 and is chamfered at 124. A stop nut 125 is threaded into the internally threaded portion 116 of end cap 115 and surrounds clamping member 119 which slides therein. Carried within the central boring 121 of clamping member 119 is sliding member 126 centrally bored at 127 and bored to receive the transverse pin 128 which itself is bored at 129 and opens into boring 127. A suitable conduit 130 opens into boring 129 as will later be more fully described. Sliding member 126 is recessed at 131 to receive a hollow end plug 132 upon which is threaded the sealing collet 133. Sealing collet 133 is longitudinally slotted at 134 dividing the same into four clamping fingers 135 (Figs. 17 and 18), each finger 135 having a beveled surface 136 to be engaged by and mating with the chamfered portion 124 of clamping member 119. Threaded into hollow end plug 132 and extending past the ends of fingers 135 is hollow male member 137, having ridges at 138 and designed to enter the open end of the tube 139 which is to be formed into the 75

expansible and contractible vessel. A spring 140 carried in recess 121 urges sliding member 126 to the right as seen in Fig. 20 to engage the transverse pin 128 with the right-hand end of slots 122 in member 119.

Figs. 22 and 23 disclose a modified form of the end sealing assembly just described. In this form clamping member 119 is formed with an internal circumferential shoulder 141 against which 10 ring member 142 having the chamfered portion 124 is held by lock ring 143. Male member 137 instead of being ridged at 138 has a head 144 designed to enter tube 139 and tube 139 is bent by chamfered surface 124 over the end surface 145 of 15 head 144 as shown in Fig. 23.

With reference now to Figs. 1, 2 and 3 the hydraulic system for operating the above described embodiment of the present invention will now be described. As illustrated, a main supply line 146 20 leading from a central pumping station supplies water under pressure to a reservoir 147, the rate of supply being controlled by hand-adjusted valve 148. Air is admitted under pressure to reservoir 147 through valve 149 and any suitable gauge 150 25 is used to indicate the water level in reservoir 147. Reservoir 147 is suitably supported on legs 151. A supply line 152 controlled by a hand-adjusted valve 153 takes the water under pressure through a coupling 154 to a suitable four way 30 valve 155. From one outlet 156 of four way valve 155 a supply line 157 leads through a T coupling 158 to a T coupling 159. T coupling 159 connects to T coupling 160 on one side and is closed by plug 161 on the other. One side of T 35 coupling 160 is connected to flexible conduit 105 leading to cylinder 100. T coupling 160 connects to T coupling 161 which in turn connects through hand-adjusted valve 162 to T coupling 163 which connects through elbow 164 to the interior of 40 booster cylinder 165.

Referring now more particularly to Fig. 19, booster cylinder 165 is mounted on a bracket 166 secured to bed 11, bracket 166 forming end 167 of the booster cylinder 165. A second bracket 45 168 secured to bed 11 forms the other end 169 of booster cylinder 165. Mounted in cylinder 165 is piston 170 to which is secured a piston rod or plunger 171 which extends through end 169, suitable packing 172 and packing nut 173 preventing 50 the escape of fluid from booster cylinder 165. Bolts 174 hold the booster cylinder assembly together. Mounted on end 169 as by threaded sleeve 175 is high pressure cylinder 176 closed at its upper end by a cap 177.

55 Opening into high pressure cylinder 176 is T coupling 178. One side of T coupling 178 leads through check valve 179 and hand-adjusted valve 180 (Figs. 1 and 3) to a source of supply of water 181 such as a suitable city water main. The other side of T coupling 178 leads through check valve 182 to a pressure actuated valve 183, the pressure responsive element 184 of which connects through conduit 185 with elbow 164. 60 Pressure actuated valve 183 is connected by a conduit with a suitable pressure relief valve 186 which in turn is connected through flexible conduit 187 with conduit 130, a pressure gauge 188 being interposed in conduit 187. Pressure relief valve 186 65 70 exhausts through conduit 189 into a T coupling 190. One side of T coupling 190 connects with a hand-adjusted relief valve 191 opening into the exhaust line 192. The other side of T coupling 190 connects with T coupling 193 one side of which 75 connects through conduit 194 with the pressure

responsive element 195 of the pressure responsive valve 196. The other side of T coupling 193 connects with T coupling 197 one side of which connects through conduit 198 with the pressure responsive element 199 of pressure responsive valve 200. The other side of T coupling 197 connects with pressure responsive valve 200 which exhausts through conduit 201.

Pressure responsive valve 196 connects through hand adjusted valve 202 with T coupling 161 in 10 the supply line 157 and on the other side connects with spacer withdrawing cylinder 203 through conduit 204, cylinder 203 having a plunger 205 designed to engage arm 99 of the spacer withdrawing assembly. Pressure responsive valve 196 15 is provided with a by-pass 206 in which is connected a check valve 207.

From T coupling 158 in supply line 157 a conduit 208 leads to a valve 209 and from valve 209 a conduit 210 leads through valve 18 to one side 20 of cylinder 16. Valve 209 is mounted on a bracket 211 (Fig. 6) secured to bed 11 and is actuated by a plunger 212 which is engaged by a cam 213 which in turn is engaged by one arm 86 of slide 25 85 when in retracted position.

From the second outlet 214 of four way valve 155 a conduit 215 leads through a T coupling 216 to a second T coupling 217 one side of which connects to flexible conduit 106 and the other leads 30 through conduit 218 to the upper end of booster cylinder 165 at 219. From T coupling 216 a conduit 220 leads to valve 19 opening into cylinder 16, valve 19 being provided with a by-pass 221 35 having a check valve 222 therein.

From the third side 223 of four way valve 155 a return line 224 leads through a check valve 225 and hand-adjusted valve 226 to a return line 227 to the central pumping station.

Four way valve 155 is controlled by a suitable pilot valve 228 conveniently mounted on bed 11 40 and shown more particularly in Fig. 7. Pilot valve 228 comprised a base 229 centrally bored at 230 into which central boring opens conduit 231 leading from the top of four way valve 155, with conduit 232 leading thereto from the bottom 45 of four way valve 155, conduit 233 leading thereto from T coupling 154 in the pressure supply line 152 and an exhaust conduit 234 leading therefrom. Mounted in central boring 230 is valve member 235 designed to open and close communication with the above enumerated conduits as desired. Valve member 235 has a shaft 236 extending through valve cap 237 and carrying valve operating handle 238. Valve handle 238 has a projection 239 engaged by an actuator 240 pivoted to cradle base 23 (Fig. 5) at 241 and having an extended arm 242 designed to be engaged by a plate 243 mounted on cradle member 34. Actuator 240 is also adapted to be engaged by a finger 244 mounted on a shaft 245 which passes through the end of the cradle and is secured to the pivoted section of end plate 246 for motion therewith (Fig. 3). Also carried by end plate 246 at its non-pivoted section is shaft 247 passing 60 through the end of the cradle and adapted to be engaged by a locking lever 248 to lock the forming plates in their compressed position against the action of springs 45.

One of the hold down bolts 249 of the cradle 70 bed 23 is given a conical shape so that the operator may, if necessary, by forcing the open end of the tube to be formed into the expansible and contractible vessel over this cone, flare the open end of the tube to receive the male member 137. 75

A counter 250 may be placed, if desired, on bolts 102 of cylinder 100 and suitably connected to a moving part of the machine to record the number of expandible and contractible vessels formed by the machine.

Assuming now that the above described embodiment of the present invention is set up as described, that the various parts thereof are properly adjusted, that fluid under pressure is in the hydraulic system, that the various valves in the system are properly adjusted, that the forming plates are open (as in Fig. 9) and that the spacers are between the forming plates, then to operate this embodiment of the present invention the operator places a suitable metallic tube 139 having one end closed in the semicircular recesses 41 of forming plates 36 with its closed end fitting in the movable section of end plate 246 after flaring the open end of tube 139, if necessary, by forcing the open end of tube 139 over cone shaped bolt 249. With tube 139 in place as described the operator seizes hand hold 74 of lever 72 and forces lever 72 to the right or in clockwise direction as viewed in Fig. 9. Clockwise rotation of lever 72 rotates plates 36 and cradle members 33 and 34 in a clockwise direction and pin 76 rides upward in slot 75 of lever 72 rotating latch 77 in a clockwise direction until finger 78 engages the top of pin 61. Thereafter further clockwise movement of lever 72 acting through latch 77 rotates cradle latch member 57 in a counterclockwise direction rotating gear 66 through gear 63 and cranks 67 in a clockwise direction and stretching springs 69. Counterclockwise rotation of cradle latch member 57 acting through shaft 56, links 55 and release rod 54 rotates latches 50 in a counterclockwise direction. Before latches 50 or latch fingers 60 have reached their locked positions the adjacent edges 40 of the pairs of plates 29 and 36 have met and thereafter clockwise rotation of lever 72 acts to move latches 50 and latch fingers 60 into their locked positions, latches 50 passing over tongues 51 on plates 36 and latch fingers 60 entering recesses 83 in extension 73 of top member 35. As latches 50 and latch fingers 60 reach their locked positions the under edge of extension 73 passes onto shoulder 82 of lever 72 and pivot 76 enters the offset portion of slot 75 effecting a strong and secure lock of both cradle and forming plates.

As cradle member 34 reaches its locked position plate 243 secured thereto rides over arm 242 and rotates arm 242 in a counterclockwise direction (Fig. 1) about its pivot 241 and actuator 240 is moved to the left in Fig. 5 carrying with it extension 239 of pilot valve operating lever 238 and rotating valve shaft 236 and valve member 235 to place pressure conduit 231 in communication with the top of four way valve 155 operating four way valve 155, to place supply conduit 152 in communication with supply conduit 157, and place conduit 215 in communication with return conduit 224. Fluid under pressure in conduit 157 passes through flexible connection 105 to the left side of piston 104 (as seen in Fig. 13) and forces piston 104 and piston rod 107 to the right, the fluid in cylinder 100 at the right of piston 104 exhausting through conduits 106, 215 and return conduit 224. Movement of piston rod 107 to the right moves clamp member 119, spring 140, slide member 126, clamp fingers 135, and male member 137 to the right until transverse pin 128 engages stop nut 125 as in Fig. 21 at which time male member 137 has entered tube 139 and clamp fingers 135 have passed over and surround

tube 139. Further movement of piston rod 107 to the right slides clamp member 119 over sliding member 126, compressing spring 140, forcing chamfered portion 124 of clamp member 119 over the mating angles 136 of clamp fingers 135, forcing clamp fingers 135 against the surface of tube 139 and compressing tube 139 against male member 137 to form a fluid tight joint therewith, or as in the embodiment shown in Figs. 22 and 23 the chamfered portion 124 bends the end of tube 139 over shoulder 145 of head 144 of male member 137 as in Fig. 23 to form a fluid tight joint therewith.

While fluid under pressure from conduit 151 is operating the tube end sealing means just described, fluid under pressure from conduit 151 has passed through valve 162, where its flow is properly controlled, and through elbow 164 to booster chamber 165 where it acts to raise piston 170, the fluid above piston 170 exhausting through conduits 218, 215 and return conduit 224, and also to raise plunger 171 to create a high pressure in cylinder 176 in ratio as the area of piston 170 is to the area of the end of plunger 171. High pressure fluid in cylinder 176 passes through check valve 182, check valve 179 being closed, and backs up against the closed pressure actuated valve 183 until piston 170 can no longer raise plunger 171 in cylinder 176, at which time pressure backs up behind piston 170 and the fluid under this pressure passes through conduit 185 to the pressure responsive element 184 of pressure actuated valve 183 to open valve 183. At this time owing to the adjustment of valve 162 the tube end sealing cycle above described has just been completed. With valve 183 open fluid under high pressure from cylinder 176 passes through pressure relief valve 186, pressure gauge 188, conduit 187, conduit 130 and through boring 127 and male member 137 into tube 139 where the fluid under high pressure acts to form bulges in the tube 139 between the pairs of forming plates 29 and 36 as seen in Fig. 15. As soon as the bulges have been formed in tube 139 pressure backs up in conduit 187 and pressure relief valve 186 opens and relieves excessive fluid pressure through conduit 189 where the pressure backs up against the closed pressure actuated valve 200, any excess pressure fluid exhausting through valve 191 and conduit 192, valve 191 being suitably adjusted to obtain the proper pressure behind valve 200. The fluid under pressure backing up behind valve 200 passes through conduit 194 into the pressure responsive element 195 of valve 196 and opens valve 196. After the valve 196 is open the pressure behind valve 200 transmitted through conduit 198 into the pressure responsive element 199 of valve 200, opens valve 200 allowing exhaust from relief valve 186 to maintain the pressure in tube 139 constant.

As soon as valve 196 is opened fluid under pressure from conduit 157 properly controlled by valve 202 passes to cylinder 203 and raises plunger 205 and rotates arm 99 in a counterclockwise direction as seen in Fig. 6 rotating shaft 96' and link 95 in the same direction, link 95 acting through link 93 to move slide 85 to the left and withdraw spacers 92 from between the pairs of plates 29 and 36. As spacers 92 reach their withdrawn position valve 200 opens releasing the pressure in conduit 194 and valve 196 closes.

Movement of slide 85 to the left in Fig. 6 moves arm 86 of slide 85 over cam 213 and depresses plunger 212 to open valve 209 as soon as spacers 92 reach their withdrawn position.

Opening of valve 209 admits fluid under pressure from conduit 157 through conduit 208 to conduit 210 and this fluid under pressure is properly controlled by valve 18 and admitted 5 to cylinder 16, forcing the piston in cylinder 16 to the left in Fig. 1, which in turn forces ram shaft 21 to the left engaging ram head 22 with end plate 246 and thereafter forcing end plate 246 and the pairs of forming plates 29 and 36 10 to the left against the actions of springs 45 and folding tube 139 into bends which enter the cut away portions 41' and 42 of each pair of plates 29 and 36. The fluid in cylinder 16 in front of the piston finds easy egress from cylinder 16, as the piston is moved to the left, through valve 19 and by-pass 221 and check valve 222, by-pass 221 being provided to insure that no substantial 15 resistance will be offered to the movement of the piston so that the action of ram head 22 will be 20 smooth and uniform.

As end plate 246 moves to the left it carries with it rod 247 which is then engaged and locked by lever 248 to prevent any expansive movement of the end plate 246 or of the pairs of 25 plates 29 and 36. End plate 246 also carries with it rod 245 and finger 244 and as the pairs of plates 29 and 36 reach a predetermined compacted position finger 244 engages actuator 240 (Fig. 5) and moves actuator 240 to the right 30 and rotates pilot valve handle 238 and valve member 235 to place pressure conduit 233 in communication with conduit 232 leading to the bottom of four way valve 155, which places supply conduit 152 in communication with conduit 35 215 and places conduit 157 in communication with return conduit 224. Fluid under pressure in conduit 215 passes through T coupling 216 into conduit 220 and through valve 19 into cylinder 16 where it moves the piston to the right in Fig. 40 1 withdrawing ram shaft 21 and ram head 22 from end plate 246, the fluid on the other side of the piston exhausting through valve 18, conduit 210, valve 209, conduit 208, and conduit 157 into the return conduit 224.

45 Release of pressure in conduit 157 releases pressure in conduit 185 and valve 183 closes. At the same time fluid under pressure in conduit 215 passes through conduit 218 into the top of booster cylinder 165 at 219 and forces piston 50 170 downward (Fig. 19) the fluid beneath piston 170 exhausting through conduit 157 into the return conduit 224. As piston 170 moves downward plunger 171 moves downward in cylinder 176 and city water from main 181 suitably controlled by valve 180 opens check valve 179 and 55 fills cylinder 176 for the next cycle of operation. Closing of valve 183 allows pressure relief valve 186 to drain the liquid from the pipes leading to the now completed expansible and contractible metallic vessel and lack of pressure in exhaust conduit 189 allows valve 200 to close. Fluid under pressure has meanwhile been supplied 60 from conduit 215 through conduit 106 to the right side of cylinder 100 (Fig. 13) forcing piston 104 to the left, fluid to the left of piston 104 exhausting through conduits 105 and 151 to return conduit 224. Motion of piston 104 to the left moves piston rod 107 to the left, drawing clamp member 119 to the left, disengaging chamfered surface 124 from mating surfaces 136 and 65 allowing clamping fingers 135 to disengage the surface of the tube end 139 of the now completed expansible and contractible vessel. Clamp member 119 continues to move to the left 70 until the right ends of slots 122 engage trans-

verse pin 128 and thereafter sliding member 126 is drawn to the left pulling male member 137 out of the tube end 139 and the tube end sealing assembly is returned to its initial position.

The operator now grasps hand hold 74 of lever 72 and moves it in a counterclockwise direction as seen in Fig. 12 a small force being sufficient to start pivot 76 down slot 75 and move shoulder 82 out of engagement with the under surface of extension 73. Thereafter springs 69, rotate 10 cradle latch member 57 in a clockwise direction in Fig. 9, which frees fingers 60 from recess 83, frees pin 61 from fingers 78 and 79, rotates latches 50 in a clockwise direction, freeing tongues 51 and unlocking each pair of plates 29 15 and 36, and rotates cranks 67 through gears 63 and 66 in a counterclockwise direction releasing the tension in springs 69. Further counterclockwise movement of lever 72 rotates cradle members 33 and 34 and plates 36 in a 20 counterclockwise direction (Figs. 8 and 9) separating each pair of plates and the operator then removes the finished expansible and contractible vessel. The operator now depresses locking lever 248 disengaging rod 247 and allowing springs 45 to force the pairs of plates 29 and 36 apart and to return the pairs of plates to their initial positions where they are stopped by the stop sleeves 30, 32 and 38 before referred to.

30 The pairs of plates 29 and 36 being now in their expanded and initial positions the operator grasps lever 98 and rotates it in a clockwise direction (Fig. 6) which rotates shaft 96', link 95 and arm 99 in a clockwise direction, link 95 acting through link 93 to move slide 85 to the right, closing valve 209 and inserting spacers 92 between the pairs of plates 29 and 36, arm 99 depressing plunger 205 and forcing the fluid out of cylinder 203 through check valve 207 and bypass 206, valve 186 then being closed, through conduit 157 into the return conduit 224 and thereafter the operator manually rotates pilot valve 235 to its neutral or initial position using lever 238.

45 The apparatus of the present invention just described is now in position to commence another cycle of operation upon the proper insertion of the tube and the closing of the cradle as described above.

50 As will be apparent, adjustment of the hand-operated valves heretofore referred to enables the rate of flow theretofore and the development of pressure theretofore to be nicely predetermined so that the desired intervals of time will transpire between the successive operations in the sequence described, and where pressure responsive valves are used proper selection of the actuating pressure as well understood in the art will effect a like result.

60 It will now be apparent that the present invention provides a novel hydraulic press for forming expansible and contractible corrugated metallic vessels in which the several steps are performed automatically at the proper time. 65 Upon closing of the forming plates means are automatically actuated to close the open end of the tube after which controlled hydraulic pressure, supplied by novel pressure booster means, is admitted automatically to the interior of the 70 tube to form bulges in the tube between the pairs of forming plates. The spacers between the pairs of forming plates are then automatically removed and thereafter novel means are automatically actuated to compress the pairs of 75

forming plates to form the expansible and contractible corrugated vessel. Novel automatic means are then provided to reverse the action of the compressing means as soon as the corrugated vessel is formed, to drain the liquid under pressure from the system leading to the finished vessel and withdraw the tube end sealing means. Novel means are provided for manually interposing the spacers between the several pairs of forming plates before the start of the forming cycle, it also being apparent that the present invention provides novel means for locking the forming plates of each pair together and novel means for carrying the forming plates to allow their ready removal.

To those skilled in the art changes in or modifications of the above described illustrative embodiment of the present invention will now be suggested without departing from the inventive concept of the present invention. For instance if metallic tubes having both ends open are to be formed into the expansible and contractible corrugated metallic vessel then instead of using an end plate 246, as described, a second end sealing assembly would be used and properly timed in the cycle to close the end of the tube before hydraulic pressure was admitted at the other end of the tube or both end sealing devices could be timed to operate together and to both admit hydraulic pressure to the tube at the same time. In such a situation as this the second end sealing assembly, with proper pressure booster means, as described, would be mounted on ram shaft 21 in place of ram head 22 and would have the dual function of both end sealing the tube and compressing the forming plates to form the expansible and contractible metallic vessel. Further and other changes in the hydraulic system, in the spacer assembly or in the various locking devices will now be suggested, and therefore to determine the scope of the present invention reference should be had to the appended claims.

What is claimed is:

1. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, and means for automatically closing the open end of a tube supported in said plates when said plates are in locked position including a valve, means operative by said second named frame for operating said valve as said plates are locked together, a cylinder and piston, and tube end sealing means actuated by said piston when said valve places said source of hydraulic pressure in communication with the said cylinder to move said piston to bring said tube end sealing means into sealing engagement with the open end of the tube.

2. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are in locked position, said sealing means providing a conduit com-

municating with the interior of said tube, a valve, means in communication with said source of hydraulic pressure for increasing the pressure thereof to a bulging pressure, and means actuated by said second named frame to operate said valve and connect said source of hydraulic pressure with said means for providing a bulging pressure, said means for developing bulging pressure communicating with the interior of said tube through said end sealing means. 10

3. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are in locked position, said sealing means providing a conduit communicating with the interior of said tube, a valve, means in communication with said source of hydraulic pressure for increasing the pressure thereof to a bulging pressure, means actuated by said second named frame to operate said valve and connect said source of hydraulic pressure with said means for providing a bulging pressure, and means for connecting said means for developing bulging pressure through said tube end sealing means to the interior of the tube only after said sealing means seals the end of the tube. 20

4. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are in locked position, a valve, a pressure booster adapted to be connected to the interior of said tube through said sealing means, a pressure relief valve between said pressure booster and said sealing means, and means actuated by said second named frame for automatically operating said first named valve to connect said source of hydraulic pressure to said pressure booster as said plates are locked together, said pressure booster communicating with the interior of said tube through said sealing means and said pressure relief valve operating to maintain a substantially uniform pressure in the tube while bulges are being formed in said tube between said plates. 45

5. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, spacers adapted to be inserted between the respective pairs of plates, means for sealing the open end of a tube supported in said plates when said plates are locked together, a cylinder and piston for withdrawing said spacers, means actuated by said second named frame as said plates are locked together for connecting said source of hydraulic pressure with the interior of said tube to bulge said tube between said plates, and means automatically connecting said source of 50

hydraulic pressure with said cylinder to actuate said piston and withdraw said spacers from between said plates after bulging pressure has been established in said tube.

- 5 6. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, spacers adapted to be inserted between the respective pairs of plates, a cylinder and piston, means actuated by said piston for sealing the open end of a tube supported in said plates when said plates are locked together, a second cylinder and piston for operating said spacers, a valve, means actuated by said second named frame for operating said valve to connect said source of hydraulic pressure with said first named cylinder to move said piston and bring said sealing means into sealing position, means for thereafter connecting said source of hydraulic pressure with the interior of said tube to bulge said tube between said plates, and means for connecting said source of hydraulic pressure with said second named cylinder to withdraw said spacers after said bulge forming pressure has been established in said tube.

7. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, spacers adapted to be inserted between the respective pairs of plates, a cylinder and piston, means actuated by said piston for sealing the open end of a tube supported in said plates when said plates are locked together, a second cylinder and piston for operating said spacers, a valve, means actuated by said second named frame for operating said valve to connect said source of hydraulic pressure with said first named cylinder to move said piston and bring said sealing means into sealing position, means for thereafter connecting said source of hydraulic pressure with the interior of said tube to bulge said tube between said plates, means for connecting said source of hydraulic pressure with said second named cylinder to withdraw said spacers after said bulge forming pressure has been established in said tube, a ram for moving said plates axially, a piston and cylinder for operating said ram, and means actuated by the withdrawal of said spacers for connecting said source of hydraulic pressure with said last named cylinder.

8. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, spacers adapted to be inserted between the respective pairs of plates, means for sealing the open end of a tube supported in said plates when said plates are locked together, a cylinder and piston for withdrawing said spacers, a ram for moving said plates axially, a cylinder

and piston for operating said ram, means actuated by said second named frame as said plates are locked together for connecting said source of hydraulic pressure with the interior of said tube to bulge said tube between said plates, means connecting said source of hydraulic pressure with said first named cylinder to withdraw said spacers only after bulge forming pressure has been established in said tube, and means actuated by the withdrawal of said spacers for connecting said source of hydraulic pressure with said second named cylinder to move said ram and displace said plates axially.

9. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, spacers adapted to be inserted between the respective pairs of plates, means for sealing the open end of a tube supported in said plates when said plates are locked together, a cylinder and piston for withdrawing said spacers, a ram for moving said plates axially, a cylinder and piston for operating said ram, means actuated by said second named frame as said plates are locked together for connecting said source of hydraulic pressure with the interior of said tube to bulge said tube between said plates, means connecting said source of hydraulic pressure with said first named cylinder to withdraw said spacers only after bulge forming pressure has been established in said tube, means actuated by the withdrawal of said spacers for connecting said source of hydraulic pressure with said second named cylinder to move said ram and displace said plates axially, and means actuated by the axial movement of said plates to reverse the direction of movement of said ram when said plates reach a predetermined position.

10. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are in locked position, and means operable by said hydraulic pressure for admitting hydraulic pressure to the interior of said tube to form bulges therein operable and only after said sealing means is in sealing position.

11. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are in locked position, and means actuated by the movement of said second named frame for hydraulically operating said sealing means to move the same into sealing position.

12. In an apparatus of the character described, in combination with pairs of cooperating forming plates, a frame on which corresponding plates

- of said pairs are slidably mounted, a pivotally mounted frame on which the other corresponding plates of said pairs are slidably mounted, a source of hydraulic pressure, means for locking the plates of said pairs together, means for sealing the open end of a tube supported in said forming plates when said plates are locked together, spacers adapted to be inserted between the respective pairs of plates, means for admitting 5 hydraulic pressure to the interior of said tube to form bulges in said tube, and means for automatically removing said spacers from between said plates operative only after bulge forming pressure has been established in said 10 tube.
13. In an apparatus of the character described, in combination with pairs of cooperating forming plates, a frame on which corresponding plates of said pairs are slidably mounted, a pivotally 15 mounted frame on which the other corresponding plates of said pairs are slidably mounted, a source of hydraulic pressure, means for locking the plates of said pairs together, means for sealing the open end of a tube supported in said 20 plates when said plates are locked together, spacers adapted to be inserted between the respective pairs of plates, means for admitting hydraulic pressure to the interior of said tube to form bulges in said tube, automatic means 25 for withdrawing said spacers operative only after bulge forming pressure has been established in said tube, and hydraulic means actuated automatically by the withdrawal of said spacers for moving said plates axially to form corrugations 30 in the bulged tube.
14. In an apparatus of the character described, in combination with pairs of cooperating forming plates, a frame on which corresponding plates of said pairs are slidably mounted, a pivotally 35 mounted frame on which the other corresponding plates of said pairs are slidably mounted, a source of hydraulic pressure, means for locking the plates of said pairs together, means for sealing the open end of a tube supported in said plates when said plates are locked together, hydraulic means automatically actuated when said sealing means are in sealing position to form bulges in said tube, and hydraulic means automatically actuated only after bulges 40 have been formed in said tube for moving said plates axially to form corrugations in the bulged tube.
15. In an apparatus of the character described, in combination with pairs of cooperating forming plates, a frame on which corresponding plates of said pairs are slidably mounted, a pivotally 45 mounted frame on which the other corresponding plates of said pairs are slidably mounted, a source of hydraulic pressure, means for locking the plates of said pairs together, means for sealing the open end of a tube supported in said plates when said plates are locked together, hydraulic means automatically actuated when said sealing means are in sealing position to form 50 bulges in said tube, hydraulic means automatically actuated only after bulges have been formed in said tube for moving said plates axially to form corrugations in the bulged tube, and means actuated by said plates for reversing the operation 55 of said last named means when said plates have reached a predetermined position.
16. In an apparatus of the character described, in combination with pairs of cooperating forming plates, a frame on which corresponding plates 60 of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are locked together, and means connected to said source of hydraulic pressure for increasing said pressure to a bulge forming pressure and then introducing said bulge forming pressure into the interior of said tube including a cylinder and a piston, a second piston of smaller area than said first named piston and actuated thereby, a cylinder for said 65 second named piston adapted to be placed in communication with said tube, means actuated by said second named frame as it is moved into locked position to connect said source of hydraulic pressure with said first named cylinder, 70
- 75

and means actuated by the pressure developed in said first named cylinder for admitting bulge forming pressure from said second named cylinder to the interior of said tube.

- 5 20. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together, means for sealing the open end of a tube supported in said plates when said plates are in locked position, 10 and means for introducing hydraulic pressure to the interior of said tube to form bulges therein actuated by said second named frame as the same is moved into plate locking position.

21. In an apparatus of the character described, 20 in combination with pairs of cooperating forming plates, a frame on which corresponding plates of said pairs are slidably mounted, a pivotally mounted frame on which the other corresponding plates of said pairs are slidably mounted, a source of hydraulic pressure, means for locking the plates of said pairs together including a lock for each pair of forming plates, a lock mounted on said first named frame and adapted to engage said second named frame, means transmitting the movement of said frame lock to said plate locks, and means carried by said second named frame for actuating said frame lock when the plates of said pairs are moved into cooperative relationship.

- 35 22. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means actuated by said second named frame for locking the plates of said pairs together, means for sealing the end of a tube supported in said plates when they are 40 locked together, means connected to said source of hydraulic pressure for increasing said pressure to a bulge forming pressure and then admitting said bulge forming pressure to the interior of said tube, means for moving said plates

- 45 axially to form corrugations in the bulged tube, and hydraulic means actuated by said second named frame as it moves into plate locking position for effecting sequential operation of said sealing means, said pressure admitting means 55 and said plate moving means.

23. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means actuated by said second named frame for locking the plates of said pairs together, means for sealing the end 60 of a tube supported in said plates when they are locked together, means connected to said source of hydraulic pressure for increasing said pressure to a bulge forming pressure and then admitting said bulge forming pressure to the interior of said tube, and hydraulic means actuated by said second named frame as it moves into plate locking position for effecting sequential operation of said sealing means and said pressure admitting means.

- 70 24. In an apparatus of the character described,

in combination with pairs of cooperating forming plates, a frame on which corresponding plates of said pairs are slidably mounted, a pivotally mounted frame on which the other corresponding plates of said pairs are slidably mounted, a source of hydraulic pressure, means actuated by said second named frame for locking the plates of said pairs together, means for sealing the end of a tube supported in said plates when they are locked together, means connected to said source of hydraulic pressure for increasing said pressure to a bulge forming pressure and then admitting said bulge forming pressure to the interior of said tube, means for withdrawing said spacers, means for moving said plates axially to form corrugations in the bulged tube, and hydraulic means actuated by said second named frame as it is moved into plate locking position for effecting sequential operation of said sealing means, said pressure admitting means, said spacer withdrawing means, and said plate moving means.

25 25. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means actuated by said second named frame for locking the plates of said pairs together, means for sealing the end of a tube supported in said plates when they are locked together, means connected to said source of hydraulic pressure for increasing said pressure to a bulge forming pressure and then admitting said bulge forming pressure to the interior of said tube, means for withdrawing said spacers, means for moving said plates axially to form corrugations in the bulged tube, and hydraulic means actuated by said second named frame as 30 it is moved into plate locking position for effecting sequential operation of said pressure admitting means, said spacer withdrawing means, and said plate moving means.

35 26. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means actuated by said second named plates for locking the plates of said pairs together, means for sealing the end of a tube supported in said plates when said plates are locked together, means connected to 45 said source of hydraulic pressure for increasing said pressure to a bulge forming pressure and then admitting said bulge forming pressure to the interior of said tube, spacers adapted to be inserted between said plates, means for withdrawing said spacers, means for moving said plates axially to form corrugations in the bulged tube, hydraulic means actuated by said second named frame as it is moved into plate locking position 50 for effecting the sequential operation of said sealing means, said pressure admitting means, said spacer removing means, and said plate moving means, and means movable with said plates for actuating said last-named means to withdraw said plate moving means, release said pressure in said tube and withdraw said end sealing means.

60 27. In an apparatus of the character described, in combination with pairs of cooperating forming plates, a frame on which corresponding plates 65

70

75

of said pairs are slidably mounted, a pivotally mounted frame on which the other corresponding plates of said pairs are slidably mounted, a source of hydraulic pressure, means actuated by 5 said second named plates for locking the plates of said pairs together, means for sealing the end of a tube supported in said plates when said plates are locked together, means connected to 10 said source of hydraulic pressure for increasing said pressure to a bulge forming pressure and then admitting said bulging pressure to the interior of said tube, means for moving said plates axially to form corrugations in the bulged tube, 15 hydraulic means actuated by said second named frame as it is moved into plate locking position for effecting the sequential operation of said sealing means, said pressure admitting means, and said plate moving means, and means movable with said plates for actuating said last- 20 named means to withdraw said plate moving means, release said pressure in said tube and withdraw said end sealing means.

28. In an apparatus of the character described, in combination with pairs of cooperating forming plates, a frame on which corresponding plates of said pairs are slidably mounted, a pivotally mounted frame on which the other correspond-

ing plates of said pairs are slidably mounted, a source of hydraulic pressure, means for locking the plates of said pairs together, means for sealing the open end of a tube supported in said plates when said plates are in locked position, 5 means for increasing said pressure to a bulging pressure, and means automatically actuated by said last named means for admitting said pressure to the interior of the tube only when the bulging pressure has been developed by said last 10 named means.

29. In an apparatus of the character described, in combination with pairs of cooperating forming plates, a frame on which corresponding plates of said pairs are slidably mounted, a pivotally mounted frame on which the other corresponding plates of said pairs are slidably mounted, a source of hydraulic pressure, means 15 for locking the plates of said pairs together, means for sealing the open end of a tube supported in said plates when said plates are in locked position, and means actuated by the movement of said second named frame for increasing said pressure to a bulging pressure and then admitting said pressure to the interior of the 20 tube.

JEAN V. GIESLER.
